IGNITION APPARATUS FOR INTERNAL-COMBUSTION ENGINES.

1,125,971.

Specification of Letters Patent.

Patented Jan. 26, 1915.

Application filed January 21, 1913. Serial No. 743,245.

To all whom it may concern:

Be it known that I, IRVIN J. DAILY, a citizen of the United States, and a resident of Indianapolis, county of Marion, and State 5 of Indiana, have invented a certain new and useful Ignition Apparatus for Internal-Combustion Engines; and I do hereby declare that the following is a full, clear, and exact description thereof, reference being 10 had to the accompanying drawings, in which like letters refer to like parts.

The object of this invention is to provide a simplified and durable device for producing the initial spark by magneto or generator 15 to start internal combustion engines, and to dispense with the necessity of using batteries in starting such engines. It furnishes the required hot spark to ignite the charge in the cylinder at the exact time desired and for which it is set, entirely without regard to the speed with which the wheel is turned over to produce the compression and it is so constructed that it produces the 20 spark equally well whether driven forward or backward.

In many engines it is difficult to turn the wheel entirely over, and the wheel is turned backward, but before reaching full compression, the charge is exploded by use of a battery. When the engines are started in this 30 manner an ordinary magneto cannot be used to produce the spark and it is always necessary to have a battery; but with my invention the magneto, either make and break or jump spark, will furnish the spark at whatever point of compression desired, no matter how slowly the wheel is turned back, and the use of the battery for starting may be entirely dispensed with.

In order to get the best results and the full force of the explosion, the engines are so constructed that, while running, the explosion of the charge takes place below or before the shaft reaches the dead center, and 45 momentum of the fly wheel always carries the shaft over; but when starting the engine it is difficult sometimes for the operator to give the fly wheel sufficient momentum to carry the shaft over when the initial explosion takes place, and if it does not have the required speed the wheel kicks back, and

often injures the operator. With my invention, however, the initial spark on engines so constructed is held back until after the shaft is above dead center, so that when the explosion takes place the wheel is bound to move forward, and it is absolutely impossible to have any kick backward, while after the engine is started the explosions all take place below dead center at the point intended in 55 the construction of the engine. If, however, the initial explosion does not furnish enough speed to the wheel so that the magneto will furnish a hot enough spark to fire the engine when the second explosion should take place, 60 my invention will continue to furnish sparks for as many additional explosions as may be necessary. This feature of my invention is especially useful where compressed air is used to start the engine. Sometimes the 65 compressed air turns the wheel over so slowly that the magneto as ordinarily attached will not furnish any spark at all or at least not hot enough to explode sufficiently the charge, while with my invention 70 the necessary hot spark is furnished at the point desired, no matter how slowly the wheel is moving, and it will continue to furnish these sparks just as long as the operator desires.

The chief feature of my invention is in the spring construction. The spring used for the purpose of giving the necessary quick impulse to the armature to produce the spark, is not attached at either end, and is 75 so arranged that the proper tension upon it can be produced when the driving wheel is moved in either direction, either forward or backward; and when the tension is released, it will always turn the armature forward in 80 the direction it is intended to run when the engine is in full operation. This feature enables the magneto to be easily attached and operated, because it does not have to be set so that the driving wheel is turned in one 85 particular direction.

Another and exceedingly important feature of the invention is that the injurious shock which in kindred devices is occasioned by stopping the recoil of the spring, is practically eliminated by this force coming 90 against the other end of the spring, which

so cushions the shock that no injury is done to the mechanism. In this device the armature is spring actuated, and also spring cushioned, and, in fact, the same spring performs both of these functions; so that the mechanism is not subject to the shock of the sudden stop of the armature, which necessarily occurs in all of the other kindred devices.

0 The nature of the invention will be understood from the accompanying drawings and the following description and claims.

In the drawings, Figure 1 is a side elevation of an internal combustion engine 15 equipped with said invention. Fig. 2 is a side elevation of the magneto and associated parts on an enlarged scale. Fig. 3 is a transverse section on the line 3—3 of Fig. 2, showing the parts in one position. Fig. 4 is 20 a similar view showing the parts in another position. Fig. 5 is a perspective view of a part of the casing and the spring and stops therein. Fig. 6 is a plan view of what is 25 shown in Fig. 5 with the spring actuated to the dotted line position. Fig. 7 is a longitudinal central section of the right-hand portion of what is shown in Fig. 2.

There is shown herein an internal combustion engine having cylinders 10 and 30 crank case 11 with a bracket 12 on the crank case which carries the magneto 13 and crank shaft 14. The magneto is a low tension magneto of ordinary type with an inductor shaft 15, magnets 16 and an end plate 17 of 35 the main casing of the magneto. The inductor shaft of the magneto may be driven by any suitable means. The means shown is through a sprocket wheel 20 which is loosely mounted on the inductor shaft 15 40 and has extending outwardly from it a pin 21 which projects between the ends 22 and 23 of a spring 24 coiled about the hub 25 of a cylinder or casing 26 and which is secured on the shaft 15 by a set screw 27. The 45 spring is coiled loosely about the hub 25 and its two ends 22 and 23 lie on opposite sides of a pin 28 which extends inwardly from the end wall of the casing 26 and is rigid. In this manner the inductor shaft 15 is 50 yieldingly actuated and under resistance to the rotation of the shaft 15, the spring will be changed from the full line position shown in Fig. 5 to the dotted line position shown in Fig. 6, the pin 28 holding the end 23 of the 55 spring stationary and the pin 21 on the sprocket wheel 20 moving the end 22 of the spring and thus tending to coil more tightly the spring around the sleeve 25. The spring is very loosely coiled around the sleeve 25, as 60 shown in Fig. 6, and it is held in place by a roller 29 loosely mounted on a pin 30 in the case 26. This not only makes a yielding drive, but also pushes the device against the back stroke of the shaft 15.

The shaft 15 has secured on it a stop disk 6 31 which has semi-circular cam projections 32 on one side and a stop block 33 on the other side in position to engage the hooked end of an arm or pawl 34 spring mounted on a pin 35 extending outwardly from the upper portion of the end plate 17. The hooked end of the pawl 34 has lateral play, as shown in Fig. 7. This play or movement is attained by the pawl 34 having a large opening through it for the pin 35 and a spring 36, said spring lying within said opening and around the pin 35. The pawl 34 has a laterally extending flange 134 on its outer side in position at times to be engaged by a cam 40 which is secured to the hub of the 80 sprocket wheel 20. The pawl 34 has a finger piece 41 whereby it is laterally adjusted.

The operation of the mechanism is as follows: Assuming the engine to be at a standstill, the operator takes hold of the finger 85 piece 41 and throws the lower end of the pawl 34 to the right, as shown in Figs. 2 and 7, that is, off of the flange 117 upon which it normally rides, in position upon the stop disk 31 and then the flange 135 overlaps the 90 cam 40. The engine is cranked or the crank shaft given a starting movement which immediately actuates the sprocket wheel 20 of the magneto. That causes the cam 40 to revolve in the direction indicated by the arrow 95 in Fig. 3. During this movement, however, the inductor shaft 14 is resisting rotation because the hooked end of the pawl is in engagement with the shoulder or stop 33 of the stop disk 31 secured on the inductor 100 shaft and it holds the inductor shaft from rotation until the cam 40 turns far enough to engage the pawl, as shown in Fig. 4, and dislodge it. During that movement, the tension of the spring 24 has been increased all 105 of the time and as soon as the pawl disengages the stop 33, the spring will give a sudden and vigorous rotary impulse to the inductor shaft of the magneto which will cause a spark in the spark plug of the engine 110 and ignite the charge at once. The above results whether the sprocket wheel 20 be actuated slowly or fast. It is immaterial how it is actuated for it can be started by hand with a slow movement and yet the 115 spring would give a sudden impulse to the inductor shaft sufficient to cause a strong spark and without the addition of any battery or other auxiliary means. It enables the battery to be dispensed with. This action of the cam dislodging the pawl, throws it automatically out of the way of the cam 40 over onto the shoulder 117 and henceforth the pawl 34 does not interfere with the 120 operation of the magneto. When it is desired again to start the engine, the pawl 34 is dislodged by hand or otherwise from its position on the shoulder 117 and thrown

over upon the disk 31. It is immaterial in what direction the sprocket wheel 20 rotates for if it goes in the opposite direction from that indicated in Fig. 3, the other shoulder 5 32 will engage the pawl 34 and prevent further rotary movement of the inductor shaft until the spring has been put under considerable tension, when again the pawl will be dislodged by the cam 40 and the spring will 10 give the necessary impulse to the inductor shaft.

The stops 22 and 23 on the disk 31 prevent back action or rotation of the inductor shaft, as they are arranged so that the hook on the 15 pawl 34 will catch one of those stops regardless of the direction in which the inductor shaft starts.

The spring 24 and the pin 28 on the armature 26 and the pin 21 on the gear 20 are 20 arranged so that the return or spring-actuated movement of the armature is not suddenly stopped, but is gradually stopped by the same spring 24, said spring thus serving as a cushioning means for stopping the 25 armature and absorbing or preventing the shock which would result if the armature was suddenly stopped.

I claim as my invention:

1. An electric generator provided with an 30 inductor shaft, a spring for causing its rotation and which is adapted to yield in both directions so as to yieldingly stop as well as actuate said shaft, and means for temporarily holding and then releasing said shaft.

2. An electric generator provided with an 35 inductor shaft, a spring for causing its rotation, and a pair of stops for limiting the action of the spring in both directions.

3. An electric generator including an in- 40 ductor shaft, a drive wheel loosely mounted on said shaft with a pin extending laterally therefrom, a casing secured on said shaft with a pin extending therefrom toward said drive wheel, a coil spring sur- 45 rounding said shaft with both ends thereof projecting radially outward and on opposite sides of both of said pins, means for temporarily holding the inductor shaft against rotary movement, and means for releasing 50 said holding means after the driving mechanism has put said spring under tension.

4. An electric generator including an in- 55 ductor shaft, a stop disk secured thereon with a plurality of stops, a pawl in position to engage one of said stops whether the shaft be turned in one direction or the other, means loosely mounted on the shaft for driving the same, a spring through which power is transmitted from said driving 60 means to the shaft, and means connected with the driving means for releasing the pawl.

5. An electric generator including an in- 65 ductor shaft, a main casing, a pin in the

casing, a pawl mounted loosely thereon so that the free end may have lateral move- 70 ment, a spring for actuating said pawl, an annular shoulder on the casing for holding the pawl out of operative position, a stop disk on said shaft in position to be engaged by the pawl when moved into operative position, means loosely mounted on the shaft for driving the same, a spring through which power is transmitted from said driv- 75 ing means to the shaft, and means connected with the driving means for releasing the pawl, said pawl being arranged so that said cam will throw it out of operative position.

6. An electric generator including an in- 80 ductor shaft, a main casing, a pin in the casing, a pawl mounted loosely thereon so that the free end may have lateral move- 85 ment, a lateral flange on said pawl, a spring for actuating said pawl, an annular shoul- 90 der on the casing for holding the pawl out of operative position, a stop disk on said shaft in position to be engaged by the pawl, a cam adapted to engage the lateral flange on the pawl, a stop disk on said shaft in position to be engaged by the pawl when moved into operative position, means loosely 95 mounted on the shaft for driving the same, a spring through which power is transmitted from said driving means to the shaft, and means connected with the driving means for releasing the pawl, said pawl being arranged so that said cam will throw it out of operative position.

7. An electric generator including an in- 100 ductor shaft, driving means loosely mounted on said shaft, means attached to said shaft which, by pressure against the same, will cause the said shaft to rotate, a spring coiled around said shaft with projecting ends, a 105 pin extending from said driving means, a pin extending from the means attached to said shaft, both of said pins projecting between the ends of said spring without the ends of said springs being attached to either of said means passing between the ends of 110 said spring and so constructed that when the pin extending from said driving means is pressed against one end of said spring, the other end of the spring will engage the other pin without regard to the direction said 115 driving means will propel the inductor shaft whether said driving means is rotated either forward or backward, and means for temporarily holding said inductor shaft from revolving with said driving means and thus 120 causing tension upon said spring that will, by the recoil thereof when said holding means is released, cause said inductor shaft to revolve at a much more rapid rate than the driving means and will cause the pin 125 from the means attached to said inductor shaft to strike the end of the spring against which the revolving means is pressing and

at practically the same time strike the pin extending from said driving means and thereby the momentum of said inductor shaft be checked without shock by the cushioned effect of said spring until the increased speed of said inductor shaft is reduced to the speed of the driving means.

8. An electric generator including an inductor shaft, a driving means loosely mounted on said shaft, a pin extending from said driving means, a casing attached to said shaft, a pin extending from said casing, and a spring coiled around said shaft and so constructed at each end that the pin extending from the driving means and also the pin extending from the casing will both project between the ends of said spring in such a manner that without the ends of said spring or either of them being attached, the pin extending from the driving means, when said driving means is rotated upon said shaft, will press against one end of said spring and when the driving means is rotated in the other direction, will press against the other end of said spring, and when said pin attached to said driving means is pressed against one end of the spring, the pin attached to said casing will always press against the other end of the spring than the one against which the driving means is pressing and will cause the inductor shaft to rotate with the same speed as the driving means, and when the inductor shaft is held from rotating with the driving means, a tension is placed upon said spring and when that tension is released, the recoil of the spring will cause the inductor shaft to rapidly rotate until the pin attached to said casing strikes the other end of said spring, which by reason of not being attached to said driving means, and the other end at the same time striking against said driving means, will give a cushioned check to the speed of said inductor shaft down to the speed of said driving means.

9. An electric generator including an inductor shaft, a driving means loosely mounted on said shaft, a pin extending from said driving means, a casing attached to said shaft, a pin extending from said casing, and a spring coiled around said shaft and so constructed that the pin extending from the driving means and the pin extending from the casing will both project between the ends of said spring, so that when said driving means is revolved, the pin extending from the driving means will press against one end of the spring, and if the driving means is turned to the opposite direction, the pin extending from it will press against the other end of said spring, and whenever the driving pin attached to said driving means presses against one end of said spring, the pin extending from the casing will press

against the other end of said spring, and thereby the inductor shaft will be turned by the driving means, and when said inductor shaft is held from rotating, a tension will be placed upon said spring, and when said tension is released, the recoil of said spring will cause said inductor shaft to revolve at a rapid speed, until the pin attached to said casing strikes the other end of the spring, which serves as a yielding or cushioned stop, to stop or check up the speed of said inductor shaft to correspond with the speed of said driving means.

10. An electric generator including an inductor shaft, a driving means loosely mounted on said shaft, a pin extending from said driving means, a casing attached to said shaft, a pin extending from said casing, a spring coiled around said shaft and so constructed at each end that said pin extending from the side of said driving means and also said pin extending from the casing will both project between the ends of said spring, so that the pin attached to the driving means, when said driving means is turned around the shaft, will press against one end of said spring, and if the driving means is turned in the opposite direction, the pin attached to the driving means will press against the other end of the spring, and whenever the pin attached to said driving means presses against one end of said spring, the pin extending from the casing will press against the other end of the spring, and when said inductor shaft is held from rotating, the turning of the driving means will put a tension upon said spring, means for holding said inductor shaft while the driving means is putting tension upon said spring, means for releasing said holding means when the desired tension is acquired, means whereby the momentum given to said inductor shaft by said spring, when released, is stopped, or checked up to the speed of the driving means, by having the pin attached to said casing strike against the other end of said spring.

11. An electric generator provided with an inductor shaft, a spring for causing its rotation, and means for limiting the rotation of said shaft in either direction.

12. An electric generator provided with an inductor shaft, a spring for causing its rotation, means for temporarily holding said shaft when rotated in either direction, and means for releasing said holding means.

13. An electric generator provided with an inductor shaft, a spring through which power is transmitted to rotate said shaft, and means loosely engaged by said spring when moved in either direction for yieldingly actuating and stopping said shaft, as desired.

14. An electric generator provided with

an inductor shaft, a spring through which power is transmitted to rotate said shaft and arranged to cause the rotation in either direction, and means engaged by but not attached to said spring for actuating said shaft and stopping the same, as desired.

In witness whereof, I have hereunto

affixed my signature in the presence of the witnesses herein named.
